UNITED STATES PATENT OFFICE.

JOSEPH ALBERT DEPORT, OF PARIS, FRANCE.

GUN-CARRIAGE FOR FIELD ORDNANCE.

939,399.

Specification of Letters Patent. Patented Nov. 9, 1909.

Application filed September 22, 1908. Serial No. 454,258.

To all whom it may concern:

Be it known that I, JOSEPH ALBERT DEPORT, a citizen of the Republic of France, residing in Paris, France, have invented certain new and useful Improvements in Gun-Carriages for Field Ordnance, of which the following is a specification.

Field pieces in which there is a long recoil of the gun on its carriage, which is provided with a trail spade, are open to the objection that the horizontal range of firing is reduced to a few degrees, whether or not the carriage slides on the axle-tree or is pivoted.

When the target is outside the horizontal range through which the gun can be trained, the trail spade has to be withdrawn, involving a loss of valuable time before the spade can be driven home again sufficiently for rapid firing of the gun. This inconvenience is particularly felt when the target is in motion, as in the case of moving troops, convoys, or balloons.

The present invention relates to a construction of gun-carriage on wheels by which the aforesaid inconvenience is avoided. According to the invention there is substituted for the narrow supporting base afforded by the anchoring spades commonly used at the end of the trail, a wider supporting base obtained either by making the trail beam in two parts articulated together so as to be capable of being opened out when the gun is being placed in position, each such part having a sliding spade at its end adapted to be driven into the ground by blows, or by adding to the trail one or two legs articulated or otherwise fitted to the main carriage and provided with sliding spades of the kind aforesaid. According to circumstances the gun is made to turn on its carriage or with its carriage in order to utilize as the horizontal firing range the large angle comprised between the anchoring spades.

The invention is illustrated in the accompanying drawings in which like letters indicate like parts.

Figure 1 is a plan of a gun-carriage on wheels comprising a trail composed of two beams each articulated to the carriage and provided with a sliding spade; the full lines show the trail opened and in position for firing, while the dotted lines show it closed for traveling. Fig. 2 is an elevation thereof. Fig. 3 is a part vertical section on line M—M of Fig. 1, drawn to an enlarged scale. Figs. 4, 5, 7 and 8 are plans of modifications

respectively and Fig. 6 is a sectional detail view drawn to an enlarged scale.

The carriage consists essentially of a frame A on wheels to which the beams B B' composing the trail are articulated either by ball and socket joints or by universal joints C C' comprising two rectangular axles forming a Hooke's joint which allows the beams movement in any plane. Each trail beam carries one or more spades D D' to be driven into the ground before firing the gun. The two trail beams can be brought together and fastened to each other by means of a bolt passed through eyes E E'. A ring or 70 trail eye F is attached to one of the beams; or each beam may have such a ring, the two rings forming a single trail eye when the beams are bolted together.

The frame A is connected with the two 75 trail beams by a cross bar G G'. Fig. 3 shows the nature of the connection of this bar G G' with the beams. The bar sustains the frame at a and each end of it slides through a corresponding box b, the outer 80 surface of which is spherical and is carried in a bush c held in place by projections d on the internal surface of the hollow beam B. The latter has opposite openings e e which are of such dimensions that the bar G G' 85 can not only move through the beam but has sufficient play in cross sectional planes of the beam. A plate f screwed on the end of the bar G G' limits the extent to which the beams B B' may be drawn apart. The 90 connection a comprises a horizontal axis upon which the bar G G' can oscillate so as to be inclined according to the requirements of the beams when they are supported on uneven ground; but also this connection 95 is such as not to oppose itself to the movements of the bar G G' which accompany the opening and closing of the beams. In order to permit such movement of the bar G G', it may be composed of two parts 100 hinged together at a; the bar may also be in a single piece and the connection a arranged to slide by arranging the axis in a groove provided either in the bar G G' or in the frame of the carriage. Or the connection a may be arranged to tie the bar and the frame rigidly together, in which case the boxes b can be arranged to slide with their bushings c on the guides d. These modes of mounting the bar G G' allow the 105 play to the beams B B' necessary for moving them apart and bringing them together.

On a vertical pivot I turns a small carriage K on which are mounted the trunnions of the cradle M of the gun N. At the back of the frame A is a circular rack P struck from the pivot I as center and engaging a worm Q for training the gun. The small carriage K is provided with a suitable elevating mechanism. It is hooked to the frame to insure connection when the piece is traveling. 10 Owing to this construction the gun may have a large horizontal range, corresponding with the angle between the opened out trail beams, without the direction of the force of the recoil falling outside the supporting base provided by the spades. Owing 15 to the universal jointing of the trail beams to the frame, the gun carriage may be mounted for firing on uneven ground without inconvenience. Moreover, the construction permits a notable increase in the elevation of the gun, since the latter, in its recoil, does not foul the trail. Instead of having the training rack behind the pivot I, it may be in front thereof. 20 25 In Fig. 4 the trail beams are connected with the frame by the same articulation instead of by separate articulations. The pivot of the trail beams may also be the pivot I of the small carriage K, as shown, or it may be a separate pivot. 30

In the modification shown in Fig. 5 the axle-tree is jointed, the two parts O O being connected by a hinge as shown in section in Fig. 6, the vertical hinge pin I serving as 35 the pivot of the cradle.

Fig. 7 shows a form in which the horizontal range is increased by attaching to the carriage by an universal joint a leg R

having a sliding spade at its rear end. The point of attachment may be on the axle tree 40 as shown, or on some other part of the carriage and the leg may remain attached when the piece is traveling, or may be detached.

Fig. 8 shows a form in which two legs having sliding spades are articulated to a 45 cross bar pivoted to the carriage.

The several modifications illustrated are not intended to exhaust the forms of the invention.

Having thus described the nature of my 50 said invention and the best means I know of carrying the same into practical effect, I claim:

1. A gun-carriage on wheels comprising two beams jointed to the wheeled carriage 55 so as to extend rearwardly thereof and adapted to be brought together to form the trail, and means for anchoring each beam to the ground.

2. A gun-carriage on wheels comprising 60 two hollow beams jointed to the wheeled carriage so as to extend rearwardly thereof, a cross bar pivoted to the wheeled carriage, a ball and socket joint within each of the beams through which joint the corresponding end of the said cross bar is adapted to slide, and means for anchoring each of the said beams to the ground.

In witness whereof, I have hereunto signed my name in the presence of two 70 subscribing witnesses.

JOSEPH ALBERT DEPORT.
